RAIL BOND

Arnold J. McKernan, Richmond Hill, N. Y., and Ernest J. Sabol, Worcester, Mass., assignors to The American Steel and Wire Company of New Jersey, a corporation of New Jersey

Application March 1, 1938, Serial No. 193,370

5 Claims. (Cl. 173—278)

This invention relates to rail bonds of the type adapted to be installed by welding methods, one of the objects being to provide a bond that can be installed by any one of the common types of welding methods. Other objects may be inferred from the following disclosure.

Several specific examples of bonds embodying the features of the present invention are illustrated by the accompanying drawings, in which:

10 Figures 1 and 2 are top and side views of the first example.

Figure 3 shows the bond illustrated by the above figures as it appears when installed, this figure showing the side of the bond opposite that shown by Figure 2.

Figure 4 is a section taken from the line IV—IV in Figure 3.

Figure 5 is a view similar to Figure 2 but showing a modification.

20 Figures 6 and 7 are top and side views of the second example.

Figures 8 and 9 are top and side views of a third example.

Figures 10 and 11 are sectional views showing 25 this third example installed in two different positions.

Figure 12 is a view similar to Figures 10 and 11 but showing a modification of the third example.

The rail bond constituting the first example includes a conductor 1 made of a plurality of intertwisted wires held together at their ends by ferrules 2, the wires and ferrules being butt-welded to terminals 3. Preferably, the conductor material is copper while the terminals are made of solid steel, although this is not a necessary feature of the invention.

Each of the terminals 3 includes a head having a rail fitting side 4, the top of this head adjacent the side 4 being recessed to provide a cup 5 for receiving molten welding metal when the side 4 is fitted against a rail. Figures 3 and 4 show how the welding metal may be deposited in this cup. It will be noted that the head is constructed to provide a solid metal wall 6 between the end of the conductor 1 and the cup 5, so the welder does not have to concern himself with the problem of obtaining a firm welded union with a plurality of wires. Furthermore, the cup provided by the terminals prevents the welding metal 50 from wandering, whereby copper alloy welding rods may be used without fear of the molten metal deposited by them running off from the weld location, as it would otherwise be prone to do. Due to the provision of the cup, the bond 55 can be arc-welded with a steel electrode, flame-welded with a copper flux rod, arc-welded with a copper electrode, etc.

The terminal head is also characterized by having an outer side 7 opposite the side 4, that tapers outwardly from the conductor and

smoothly merges with the rail fitting side 4. Furthermore, the head has a top 8 that tapers downwardly away from the conductor 1. Due to this tapered construction the bond heads being disclosed are not subject to easy dislodgment 5 by dragging train equipment. This function is further aided if the welding metal is smoothly deposited in the manner shown by Figures 3 and 4.

It will also be noted that the recess providing 10 the cup 5 has a smoothly rounded contour throughout, this preventing arcing between undesirable points during welding by the electric method, and in all events promoting a sound weld. To still further promote production of a sound 15 weld, the terminals 3 are, as previously mentioned, constructed of solid metal, preferably steel, and it may now be noted that, as shown by the drawings, the terminals are relatively massive whereby the head portion provides a sufficient mass of solid metal surrounding the recess 20 providing the cup 5 to permit the terminal head to safely attain a temperature substantially as high as that to which the adjacent rail metal is heated during welding, whereby the difficulties 25 usually experienced from welding a hotter part to a colder part can be avoided.

The modification illustrated by Figure 5 involves the same parts except that the ends of the conductor 1 with their surrounding ferrules 2 30 are butt-welded to the terminals so as to extend therefrom at an angle to the part of the terminal head providing the cup 5 in such manner that the conductor may be properly arranged while the cup remains level and so performs its 35 function with maximum effectiveness. The arrangement in the illustrated case is such as to provide a smooth loop which is sometimes considered desirable.

The same parts are again involved in the case 40 of the second example illustrated by Figures 6 and 7, the difference between this and the first example being that the recess providing the cup 5 extends down the side 4 to a maximum depth centrally of the recess, this point being indicated at 5^a. The advantage of this shape is that the welding metal puddles first centrally of the weld, this desirable effect permitting the rail to attain the proper temperature, and if cold welding 45 is apt to take place it will be localized at this 50 point.

The third example, illustrated by Figures 8 through 11, constitutes another well known type of bond but is distinguished by embodying the same features included by the first example. In 55 the interests of avoiding confusion, similar numerals are used on all equivalent parts except that they are followed by the letter *a* for purposes of identification.

This third example involves a further distin- 60

guishing feature in that the rail fitting side 4^a includes a receding edge surface 9 extending upwardly from the bottom of the recess providing the cup 5^a, so that the terminal may be rocked 5 through a range of angles while the cup remains operative as a retainer for molten welding metal.

Figure 10 shows the terminal vertically installed, while Figure 11 shows it installed at an angle so that the conductor 1^a extending away therefrom can clear the type of fish-plate which projects to an extent necessitating some such arrangement.

In the case of the modification of this third example, the ends of the conductor 1^a with its 15 surrounding ferrule 2^a are butt-welded to the terminal 3^a at an angle so that it is not necessary to rock the terminal head on its rounded edge surface 9 at all times. Such rocking can be resorted to, however, in those instances where 20 joint bars project extreme distances.

It will be understood that all of the examples involve substantially the same advantages except for the specific features individually possessed, which have been described. One common feature is that the cups provided by the recessed terminals, in addition to their function of restraining the fluid welding metal from running away from the weld location, also function as measuring cups whereby the same amount of 25 welding metal may be deposited in all instances. This is otherwise very difficult for a welder to do, it being remembered that he is working on an extremely large number of installations and that the amount he deposits is ordinarily solely 30 dependent on his skill and judgment. It is true that various types of molds, detachable shields, etc., have been proposed, but none of these has proved practical in the employment of all the 35 methods of the welding art for field installation 40 at will without some specific change.

We claim:

1. A rail bond for application by electric arc-welding with either steel or copper electrodes or by flame-welding with copper flux rods, including 45 a terminal comprising a solid piece of metal having a rail head fitting side and a top that are jointly recessed to provide a cup for receiving molten metal when said side is fitted against a rail, and a stranded conductor having 50 an end fixed to said terminal outside of said cup, said terminal providing a solid wall of metal between said conductor end and said cup so that molten metal received by said cup functions only to unite said terminal to the rail, said 55 side and top of said terminal being recessed only in a smoothly curving manner to provide a contour free from corners or projections and thereby preventing arcing between undesirable points during application of the terminal by electric 60 welding methods.

2. A rail bond for application by electric arc-welding with either steel or copper electrodes or by flame-welding with copper flux rods, including 65 a terminal comprising a solid piece of metal having a rail head fitting side and a top that are jointly recessed to provide a cup for receiving molten metal when said side is fitted against a rail, and a stranded conductor having an end fixed to said terminal outside of said cup, said 70 terminal providing a solid wall of metal between said conductor end and said cup so that molten metal received by said cup functions only to unite said terminal to the rail, said side and top

of said terminal being recessed only in a smoothly curving manner to provide a contour free from corners or projections and thereby preventing arcing between undesirable points during application of the terminal by electric welding methods, outside portions of said terminal being contoured to deflect dragging train equipment so that welding metal deposited in said cup does not have to be built up to provide a deflecting surface for this purpose. 10

3. A rail bond for application by electric arc-welding with either steel or copper electrodes or by flame-welding with copper flux rods, including 15 a terminal comprising a solid piece of metal having a rail head fitting side and a top that are jointly recessed to provide a cup for receiving molten metal when said side is fitted against a rail, and a stranded conductor having an end fixed to said terminal outside of said cup, said terminal providing a solid wall of 20 metal between said conductor end and said cup so that molten metal received by said cup functions only to unite said terminal to the rail, said side and top of said terminal being recessed only in a smoothly curving manner to 25 provide a contour free from corners or projections and thereby preventing arcing between undesirable points during application of the terminal by electric welding methods and being centrally deepened so that molten welding metal 30 received by said cup will initially puddle centrally of the ultimate weld.

4. A rail bond for application by welding, including 35 a terminal comprising a solid piece of metal having a rail head fitting side and a top that are jointly recessed to provide a cup for receiving molten metal when said side is fitted against a rail, and a stranded conductor having an end fixed to said terminal outside of said cup, said terminal providing a solid wall of 40 metal between said conductor end and said cup so that molten metal received by said cup functions only to unite said terminal to the rail, said side and top of said terminal being recessed only in a smoothly curving manner to provide 45 a contour free from corners or projections and thereby preventing arcing between undesirable points during application of the terminal by electric welding methods, the parts of said terminal surrounding said cup being sufficiently 50 thick to permit them to be safely heated as hot as the rail is heated during welding of said terminal to a rail and said rail fitting side having an upwardly receding surface permitting said terminal to be rocked to different angles 55 without affecting the operativeness of said cup.

5. A rail bond for application by welding, including 60 a terminal comprising a solid piece of metal having a rail head fitting side and a top that are jointly recessed to provide a cup for receiving molten metal when said side is fitted against a rail, and a stranded conductor having an end fixed to said terminal outside of said cup, said terminal providing a solid wall of 65 metal between said conductor end and said cup so that molten metal received by said cup functions only to unite said terminal to the rail, said rail fitting side having an upwardly receding surface permitting said terminal to be rocked to different angles without affecting the operativeness of said cup. 70
